United States Patent Office.

BENJAMIN F. SHAFFER, OF DAYTON, OHIO.

Letters Patent No. 73,128, dated January 7, 1868.

IMPROVEMENT IN SWINGS.

The Schedule referred to in these Letters Patent and making part of the same.

TO ALL WHOM IT MAY CONCERN:

Be it known that I, BENJAMIN F. SHAFFER, of Dayton, Montgomery county, Ohio, have invented a new and useful Improvement in the Common Swing, by which the person swinging originates and keeps up the motion required, by pressure of the feet on a pedal attached to the swing, producing a forward motion.

The nature of my invention consists in attaching to any chair-swing or seat-swing, a pedal, to be moved by the pressure of the feet of the person who is swinging. The pedal is governed and acted upon by means of cords or ropes, which may be attached to rings in the ceiling, or, if the swing is out of doors, to a beam, or the limb of a tree, or, as in the plate, to any frame $m m' m'' l l'$, and the other ends of the cords to the pedal. The cords or ropes work on movable pulleys, which pulleys are attached to the ends of a bar, which may form the front edge of the seat of the swing, thus producing a forward movement of the swing by pressure of the feet on the pedal, while the person swinging is moving forward, and lightening the pressure as the swinger goes back.

To enable others not skilled in the art to make and use my invention, I will proceed to describe its construction and operation.

I make the seat of the swing in any convenient form $g g'$. I attach this seat to two strips of scantling, of the length equal to the height of the swing $h h'$. These strips are to be attached to hooks in the ceiling, or to any suitable frame $m m' m'' l l'$. They are hooked to the frame at the points $l l'$, so that the swing may move backward and forward freely. The seat is held in position by the bar $e e'$, which passes through the uprights $h h'$, and also held by the arms $n n'$, which are attached to $h h'$ by pins at $o o'$. I attach the cords $e e' e'' e'''$ to the ceiling, or to the framework at $k k'$. The pulleys $f f'$ are attached to the ends of the bar $b b'$, and turn freely forward and backward as the swing is moved. The cords from $k k'$ are passed down back of the pulleys and under them in their grooves, and are drawn tight and attached to the extremities of the bar on which the pedal rests at $b b'$, so that the pedal may be at a proper distance below the seat of the swing. The pedal is adjustable, and moves upon an axis, $x x'$, which is a bar passing through the strips $h h'$. It may be raised up, so that the bar $a a' a$ is against the bar $e e'$, to permit a person to be seated in the swing, after which the pedal will fall back to its place.

The swing is put in motion, by the person who swings, in this manner: On taking his seat the swing is plumb; he presses his feet on the pedal, and that produces a forward motion; as he recedes, he lightens the pressure upon the pedal, and on again commencing to move forward, he again presses upon the pedal. In this manner the forward motion is kept up and increased. The cords or ropes are attached to the ceiling or frame at points $k k'$, a distance from eighteen inches to three feet in front of the hooks or rings $l l'$ to which the strips $h h'$ are attached. The leverage is increased in proportion to the distance between the points k and $l h' l'$. The pressure of the feet of the person who is swinging, on the front edge of the pedal, tends to straighten the ropes or cords, so that on each of the pulleys there are two levers, which force the swing forward, when the swinger presses his feet on the outer or front edge of the pedal, viz, levers $b f$ and $f k$, and $b' f'$ and $f' k'$.

What I claim as my invention, and desire to secure by Letters Patent, is—

In combination with the seat $g g'$ of a swing, the hinged pedal, attached to the swing, and the cords $e e'$, fastened to the pedal and carried over pulleys on the swing-frame $h h'$, and then fastened in front of the point of suspension of the swing, said several parts being respectively constructed and arranged substantially as set forth.
